C. ORR.

ROTARY REFRIGERATING MACHINE.
APPLICATION FILED NOV. 28, 1917.

Patented Oct. 15, 1918.

FIG. 1.

FIG. 2.

Inventor:
Clark Orr,

by
Albert G. Davis
His Attorney.

UNITED STATES PATENT OFFICE.

CLARK ORR, OF FORT WAYNE, INDIANA, ASSIGNOR TO GENERAL ELECTRIC COMPANY,
A CORPORATION OF NEW YORK.

ROTARY REFRIGERATING MACHINE.

1,281,820.

Specification of Letters Patent. Patented Oct. 15, 1918.

Application filed November 28, 1917. Serial No. 204,314.

To all whom it may concern:

Be it known that I, CLARK ORR, a citizen of the United States, residing at Fort Wayne, in the county of Allen, State of Indiana, have invented certain new and useful Improvements in Rotary Refrigerating Machines, of which the following is a specification.

My present invention relates to rotary refrigerating machines of the type in which a suitable material, such as sulfur-dioxide, in the form of a saturated or approximately saturated vapor or gas is confined in a hermetically sealed container, and is in the compressor portion of the container acted upon mechanically to cause it to liquefy and lose potential energy in the form of heat which is transmitted to and dissipated by a medium outside that portion of the container, in order that the material within the container may effect refrigeration of a medium surrounding another or refrigerator portion of the container by absorbing heat therefrom as it vaporizes within that portion of the container. Besides the sulfur-dioxide or similar material mentioned, the container also has a lubricant therein for lubricating the working parts of the refrigerating machine. Such a machine is described in the U. S. patent to Audiffren & Singgrün No. 1,155,780 dated Oct. 15, 1915, and the U. S. patent to J. J. Wood, No. 1,164,245, dated Dec. 14, 1915.

The refrigerator portion of the container of such a machine contains a combined liquid and lubricant separator and my invention has particularly to do with an improvement in the construction of this portion of such a machine. This portion of the refrigerating machine contains not only liquid refrigerant, but a lubricant as well, and in the operation of such machines as heretofore constructed, the liquid refrigerant forms a layer next to the surface of the container whereas the lubricant, being lighter than the refrigerant, forms as a film on top of the refrigerant, due to the action of centrifugal force. This film of lubricant acts as a blanket and retards the evaporation of the refrigerant. In accordance with my invention, I provide within the refrigerating portion of the machine, an agitator comprising a tube having a nozzle and so mounted as to dip into the liquid adjacent the per-

ipheries of the container to deflect the same into the tube from which it is directed by the nozzle against the inside surface of the container. Such a distribution of the refrigerating liquid breaks up the film of lubricant and facilitates the evaporation of the refrigerant.

Other features of novelty which characterize my invention are pointed out with particularity in the claims annexed to and forming a part of this specification. For a better understanding of my invention, reference may be had to the following description taken in connection with the accompanying drawing, in which Figure 1 is a sectional view through the refrigerator portion of the container of a refrigerating machine, showing the separator partly in section and embodying my invention; Fig. 2 is a view of Fig. 1 taken on the sectional line 2—2, and looking in the direction of the arrows, and Fig. 3 is an end view of my agitator.

Referring to the drawing, 1 is the refrigerator portion of the hermetically sealed container of a refrigerating machine which is connected by a hollow shaft 2 to the condenser portion of the machine. Projecting into the portion 1 of the container is a hollow stationary shaft 3 on which is mounted the combined liquid and lubricant separator, which comprises a central casting 4, which provides a loose supporting bearing on the end of the hollow shaft 2, a passage 5 from the refrigerator end of the machine above the shaft 2 by which vapor from this end of the machine may pass downward and into the end of the hollow shaft, and a passage 6 at the end of the hollow shaft by which lubricant may pass from a separator chamber 7 upwardly and flow into the end of the hollow shaft. The pipe 3 passes entirely through the casting 4 and discharges against the wall of the condenser 1. The casting 4 is secured to this pipe, as will be seen from Figs. 1 and 2, whereby the separator is held stationary with this pipe. A cylindrical receiver 8 open at its top is mounted on the casting 4, the bottom of this receiver being formed by this casting. A smaller cylindrical receiver 9 is mounted within the receiver 8 adjacent its forward wall, that is, that wall toward which the outer shell of the container moves as is indicated by the arrow in Fig. 2. The casting

4 also forms the bottom of this receiver 9. A tube 10 provides communication between the receiver 9 and the separator chamber 7.

A fin-shaped collector or scoop 11 is mounted on the upper edge of the receiver 9 and extends upwardly into a revolving annulus of refrigerating liquid and lubricant in the container 1. This collector or scoop 11 is provided with slots 12 and is tapered from the center toward the forward and rearward edges. The collector 11 deflects a small stream of the liquid from the inner surface of the revolving annulus of liquid by means of the slots 12 into the receiver 9. The mixed lubricant and liquid refrigerant flow down the tube 10 which connects the receiver 9 with the separating chamber 7, into this separating chamber where the lubricant and liquid refrigerant are separated by gravity, the liquid refrigerant being the heavier will settle at the bottom while the oil will occupy the upper portion of the chamber. Whenever the level of the lubricant rises above the passage 6 it will be sucked back to the compressor through the hollow shaft 2. The overflow pipe 13 extends upwardly from near the bottom of the separating chamber 7, passes through the side wall of this chamber so as to discharge liquid refrigerant against the wall of the container 1. A certain amount of liquid refrigerant carried down by the collector 10, finds its way down the outside of the receiver 9 into the receiver 8 from which it flows by a distributing pipe 14 against the wall of the container 1. The collector 10 described herein is covered by my application, Serial No. 204,315, filed concurrently herewith.

40 In accordance with my invention, an agitator 15 comprising a tube having a nozzle 16, which may be formed by flattening the end of the tube, is mounted so as to dip into the liquid adjacent the periphery of the container 1 to deflect the same into the tube from which it is directed by the nozzle against the inside surface of the container. This agitator is mounted on the receiver 8 to the rear of the collector 11 so that the end 17 of the tube, away from the flattened end 16, deflects liquid from adjacent the periphery of the container into the tube, from which it is discharged by the flattened end 16 in a flat stream against the inside surface of the container. In the operation of such refrigerating machines as described above, the liquid refrigerant such as sulfur-dioxide is heavier than the lubricant and therefore by the action of centrifugal force forms a layer next to the surface of the container whereas the oil being lighter is formed as a film on top of the sulfur-dioxide. This film of oil is held out by centrifugal force and acts as a blanket retarding the evaporation of the sulfur-dioxide. By using an agitator, such as

that described, this film of oil which has passed the collector 11 is broken up, making it much easier for the sulfur-dioxide to evaporate, and thus the capacity of the refrigerating machine at the lower temperatures is materially increased. By the use of my agitator I have found it possible to materially increase the heat absorption of such a refrigerating machine.

I desire it to be understood that my invention is not limited to the particular arrangement shown and described and is applicable to other forms of separators than that described, and I aim in the appended claims to cover all modifications that do not depart from the spirit and scope of my invention.

What I claim as new and desire to secure by Letters Patent of the United States, is:

1. In a refrigerating machine, the combination with a rotatable container and separator therein, of an agitator comprising a tube having a nozzle, said agitator being mounted so as to dip into liquid adjacent the periphery of said container and so that said nozzle directs liquid against the inside surface of the container.

2. In a refrigerating machine, the combination with a rotatable container and separator therein, of an agitator comprising a tube having a nozzle, said agitator being so mounted that the end of said tube away from said nozzle dips into liquid adjacent the periphery of said container to deflect the same into said tube from which it is directed by said nozzle against the inside surface of the container.

3. In a refrigerating machine, the combination with a rotatable container and separator therein, of an agitator comprising a tube having a flattened end, said agitator being mounted so as to dip into liquid adjacent the periphery of said container and so that the flattened end of said tube directs liquid against the inside surface of the container.

4. In a refrigerating machine, the combination with a rotatable container and separator therein, of an agitator comprising a tube having a flattened end, said agitator being so mounted that the end of said tube away from said flattened end dips into liquid adjacent the periphery of said container to deflect the same into said tube from which it is directed by the flattened end of said tube against the inside surface of the container.

5. In a refrigerating machine, the combination with a rotatable container and separator therein, of a collector mounted to convey liquid from adjacent the periphery of said container to said separator, and an agitator mounted to the rear of said collector, said agitator comprising a tube having a nozzle, the end of said tube away from said

nozzle dipping into liquid adjacent the periphery of said container to deflect the same into said tube from which it is directed by said nozzle against the inside surface of the 5 container.

6. In a refrigerating machine, the combination with a rotatable container and separator therein, of a collector mounted to convey liquid from adjacent the periphery of 10 said container to said separator, and an agitator mounted to the rear of said collector,

said agitator comprising a tube having a flattened end, the end of said tube away from said flattened end dipping into liquid adjacent the periphery of said container to 15 deflect the same into said tube from which it is directed by the flattened end of said tube against the inside surface of the container.

In witness whereof, I have hereunto set 20 my hand this 23rd day of November 1917.

CLARK ORR.
